US00D920936S

(12) **United States Design Patent** (10) Patent No.: **US D920,936 S**
Rokkam et al. (45) Date of Patent: **** Jun. 1, 2021**

(54) **HIGHER TEMPERATURE VENTED SUSCEPTOR**

(71) Applicant: **ASM IP HOLDING B.V.**, Almere (NL)

(72) Inventors: **Uday Kiran Rokkam**, San Diego, CA (US); **Sam Kim**, Chandler, AZ (US); **Saket Rathi**, Tempe, AZ (US); **Dakai Bian**, Tempe, CA (US)

(73) Assignee: **ASM IP Holding B.V.**, Almere (NL)

(**) Term: **15 Years**

(21) Appl. No.: **29/677,173**

(22) Filed: **Jan. 17, 2019**

(51) LOC (13) Cl. **13-03**

(52) U.S. Cl.

USPC **D13/182**

(57) **CLAIM**

The ornamental design for a higher temperature vented susceptor, as shown and described.

DESCRIPTION

FIG. 1 is a front perspective view of a higher temperature vented susceptor showing our new design;

FIG. 2 is a back perspective view thereof;

FIG. 3 is a left side view thereof; and,

FIG. 4 is a right side view thereof.

The dash-dash lines in FIGS. 1-4 form no part of the claimed design.

1 Claim, 3 Drawing Sheets
